Primary Examiner — Cynthia M Chin(74) *Attorney, Agent, or Firm* — Perry Hoffman(57) **CLAIM**

The ornamental design for a toy projectile launcher apparatus, as shown and described.

DESCRIPTION

FIG. 1 is a right, top, front perspective view of the toy projectile launcher apparatus of the instant invention;

FIG. 2 is a left, bottom, front perspective view thereof;

FIG. 3 is a right side elevational view thereof;

FIG. 4 is a left side elevational view thereof;

FIG. 5 is a rear view thereof;

FIG. 6 is a front view thereof;

FIG. 7 is a top view thereof; and,

FIG. 8 is a bottom view thereof.

The broken lines shown are included for the purpose of illustrating the unclaimed portions of the article that form no part of the claimed design.
